 Bernstein, LP

(57) **CLAIM**

The ornamental design for a post-fence connector, as shown and described.

DESCRIPTION

FIG. 1 is a front, side, upper perspective view of the present invention;

FIG. 2 is a top plan view thereof;

FIG. 3 is a front elevation view thereof;

FIG. 4 is a right side elevation view thereof;

FIG. 5 is a left side elevation view thereof;

FIG. 6 is a back elevation view thereof; and,

FIG. 7 is a bottom plan view thereof.

The broken lines in the drawings illustrate portions of the post-fence connector and form no part of the claimed design.

1 Claim, 7 Drawing Sheets
